PARTING STRIP FOR ROADWAYS OR THE LIKE

James H. Jacobson and Eric E. Hall,
Chicago, Ill.

Application February 10, 1934, Serial No. 710,687

2 Claims. (Cl. 94—18)

The invention relates to a parting strip or joint such as those now being employed in pavements, roadways or the like to provide means for dividing the pavement material to cause parting there-
5 of along a definite line.

The invention has among its various objects the provision of a joint for achieving the above, the same being formed in such a manner as to assist in retaining the joint in a substantially
10 perpendicular position relative to the sub-grade of the roadway during the pouring of the paving material.

An additional object is to form the joint so that it accomplishes this last mentioned ad-
15 vantage and performs the added advantage of preventing relative vertical displacement of ad-
jacent portions of the paving material at the joint after the parting of the paving material has taken place.

20 A further object of the invention is to combine a seal for the joint such as that above referred to, for sealing the crack formed, the seal having means for effecting a bond with the paving material, the seal providing means com-
25 pensating for the movement of the paving material transversely of the joint and preventing infiltration of water, dirt, etc. at the separation of the pavement sections above the seal.

The invention also has as an object the forming
30 of a parting strip or joint from a strip of ma-
terial and the fashioning of the material to pro-
vide a stool with a base for the support of the
stool, which stool is fashioned with portions sub-
stantially in the plane of the opposite edges of the
35 base and which portions are adapted to cooper-
ate with supporting stakes, the latter being
driven into the sub-grade to thus temporarily
support the device in a position substantially
40 perpendicular to the sub-grade during the pour-
ing of the paving material. It is also an object
to provide for the support of dowel or shear bars
by the joint.

The invention has these and other objects, all
45 of which will be explained in detail, and more
readily understood when read in conjunction
with the accompanying drawing, which illus-
trates one embodiment of the invention, it being
understood that changes and modifications may
50 be resorted to without departing from the spirit
of the appended claims forming a part hereof.

In the drawing:

Figure 1 is a perspective view of a joint em-
bodying the features of the invention, and,

55 Figure 2 is a vertical section through the joint

shown in Figure 1, illustrating the same as it is applied to a pavement.

The embodiment of the invention illustrated in the drawing contemplates the use of a metallic strip, generally designated 10, and termed a stool, which is fashioned to provide a base 11 for supporting the joint in a substantially vertical position upon the sub-grade 12.

This metallic strip or stool is of a width some-
what less than the thickness of the pavement slab 13
13 and thus will provide an area above the stool
along which the slab will crack or sever, and thus
cause cracking or separation of the slab along
a definite line. The stool 10 is further formed
with a vertical longitudinally extending portion 15
or wall 14, which extends upwardly from the
edge 16 of the base 11, and terminates in a connec-
tion with the longitudinally extending portion 16
which projects at an angle from the upper
termination of the wall 14 to the wall portion 17.
17 This last mentioned wall portion 17 is lo-
cated in a vertical plane which substantially cor-
responds to the plane of the edge 18 of the base.

The stool 10 is further formed to provide a
portion 19 which extends from the upper ter-
mination of the wall 17 to approximately the
center of width of the base 11, and terminates
in a longitudinally extending portion 20. This
portion 20 provides means upon which a seal,
generally designated 21, may be mounted. The
seal is provided with a plurality of indentations
22 which are employed to secure the seal to the
portion 20 of the stool 10. The material of the
seal 21 is bent to form the spaced side walls 22
and 23. The upper portion 20 of the stool 10, is
located in the space between these last men-
tioned walls. The seal is further fashioned to
provide the laterally extending, longitudinally
disposed flanges 24 and 25, each of which are
provided with a plurality of openings 26.

It will be noted from an inspection of Figure 2
that one edge, such as 27, of these openings 26
is located in substantial vertical alignment with
the wall portions, respectively designated 14 and
17, and also that the edges respectively design-
ated 15 and 16 of the base are substantially in
vertical alignment with the walls 14 and 17.

The relative arrangement of these last men-
tioned portions of the stool is employed to effect
engagement between the respective supporting
stakes designated 28 and 29, the edges 15 and 18
of the base 11, the wall portion 17, and also the
wall portion 14 extending upwardly from the
base, and will thus retain the stool 10 in its initial
position or, in other words, in a position substan-

tially perpendicular to the plane of the surface of the sub-grade. In addition, this arrangement provides means which ensures maintaining the strip in this last mentioned position during the 5 pouring of aggregate of which the pavement or slab may be formed.

The stool 10 is provided with a plurality of apertures such as that designated 30, which are disposed at intervals throughout the length of 10 the stool 10 to receive the threaded end 31, of a dowel socket 32. The opposite end of the dowel socket is formed with a downwardly projecting spike 33, the free end of which may be driven into the sub-grade. A dowel or shear bar 34 is 15 mounted in the dowel socket 32, it being understood that provision is made for allowing movement of the dowel bar 34 relatively to the socket 32 to thereby compensate for movement of the slab sections due to temperature changes and/or 20 other factors after the slab has been severed above the seal 20.

The stakes 28 and 29 are each provided with a lip 35, to thus provide stops which limit the distance which the stakes may be driven into the 25 sub-grade and assist in holding down the joint.

From the foregoing explanation of the structure it is believed evident that a parting strip is provided having means whereby it may be arranged in proper position upon the sub-grade.

30 It is further apparent that the stool is formed to provide longitudinally extending walls such as 14 and 17, which provide means for cooperating with stakes, such as 28 and 29, to thus assist in maintaining the parting strip in a substantially 35 perpendicular position relative to the sub-grade, and which will maintain the joint in this position during the pouring of the aggregate of which the pavement or slab may be formed.

40 It is further manifest that the structure described provides means whereby a dowel bar socket and a dowel bar, may be associated with said device, and in which the dowel bar is bonded in the slab, and providing means for coupling the separated sections of the slab or roadway surface 45 with each other. It is further believed that by fashioning the material of the stool to provide the portions 14, 16, 17 and 19, that a tongue and groove formation is produced in the adjacent ends of the slab sections which will effect what is 50 termed "aggregate interlock" and which will key the separated slab sections with each other and thereby assist in preventing relative displacement of the slab sections in a vertical direction.

55 Having thus described the invention, what we claim as new and desire to cover by Letters Patent is:—

1. In a concrete pavement or the like embodying the combination of a pair of adjacent con-

crete sections cast in situ upon a base material, a joint separating and sealing the space intervening between said concrete sections, said joint comprising a stool and a seal capping an edge thereof, said seal consisting of an expansible 5 member formed from a piece of flexible material bent upon itself to provide spaced walls movable relatively to each other at the bend, the material forming said walls being fashioned to provide an outwardly projecting apertured flange at the 10 lower edge of each of said walls, said stool comprising a single plate, the upper termination thereof being located within the space between the spaced walls of the seal, said plate being corrugated thereby forming alternately spaced 15 parallel ridges establishing a pair of spaced connected walls, a base for said stool, said base extending from one wall thereof to a point in a vertical line with the oppositely spaced wall, and a pair of substantially parallel supporting members 20 positioned one on each side of the joint so formed, each supporting member passing through an aperture in one outwardly projecting apertured flange of said seal and extending 25 therefrom into the base material and serving to position the joint while the plastic concrete is being poured, each of said supporting members having a bearing on the seal, a second bearing on one of the spaced walls of the stool, and a third bearing 30 on the base of the stool, said supporting members adapted to be finally embedded in the pavement material.

2. In a concrete pavement or the like embodying the combination of a pair of adjacent concrete sections, a joint separating said concrete sections, and comprising a stool and a seal capping an edge thereof, said seal being formed from a piece of material bent upon itself to provide spaced walls, an outwardly projecting flange 35 extending from each of said walls, said stool comprising a single plate located within the space between the spaced walls of the seal, extending therefrom and being corrugated forming a series of alternate parallel ridges establishing a pair of spaced connected walls, a base for said stool, said base extending from one wall thereof to a point in a vertical line with the other spaced wall, and a pair of supporting members positioned one on 40 each side of the joint so formed, each supporting member engaging an outwardly projecting 45 flange of said seal and serving to position the joint while the plastic concrete is being poured, each of said supporting members having a bearing on the seal, a second bearing on one of the spaced walls of the stool, and a third bearing 50 on the base of the stool.
